United States Patent Office.

ROBERT HOADLEY AND HENRY A. SHIPMAN, OF ANSONIA, CONNECTICUT.

Letters Patent No. 76,450, dated April 7, 1868.

IMPROVEMENT IN LAMP-BURNERS.

The Schedule referred to in these Letters Patent and making part of the same.

TO ALL WHOM IT MAY CONCERN:

Be it known that we, ROBERT HOADLEY and HENRY A. SHIPMAN, of Ansonia, in the county of New Haven, and State of Connecticut, have invented a new Improvement in Lamp-Burners; and we do hereby declare the following, when taken in connection with the accompanying drawings and the letters of reference marked thereon, to be a full, clear, and exact description of the same, and which said drawings constitute part of this specification, and represent, in—

Figure 1, a side view,

Figure 2, a vertical section, and, in

Figure 3, the plate between the base and the deflector, to illustrate its manner of construction.

This invention relates to an improvement in that class of burners designed for burning kerosene and similar oils, and consists in the peculiar construction and arrangement for the support of the chimney, and for the attachment of the deflector thereto.

To enable others to construct our improvement, we will proceed to describe the same as illustrated in the accompanying drawings.

A is the neck, to be attached to the lamp in the usual manner, and into which the base is secured. The base, B, is formed with a threaded shoulder; and from the shoulder three or more arms, C, extend up and are secured to the plate D by soldering each thereto in the usual manner. The said plate D is formed as seen in fig. 3, cut from a plate of sheet metal of the proper thickness, and with points, E E, &c., extending from its edge, and between which other similar but shorter points, F F, &c., are formed, and an opening, G, through the centre for the tube, and the balance of the plate perforated, so as to permit the air to pass freely therethrough.

The points E are, in proper dies, turned up, as seen in fig. 1, while the points F are turned down, and their ends hooked, as seen in fig. 1, to form a seat for the chimney, as seen in fig. 2. The points E, extending up into the chimney, are, from the nature of the metal, somewhat elastic, so as to bear against the inside of the chimney, to hold the chimney firmly in its seat, and yet so as to allow its removal therefrom by taking hold of the chimney, and lifting it from its side.

The tube I is inserted through the plate and base, and secured therein, and provided with a wick-adjuster, L, in the usual manner.

H is the deflector, formed so as to set upon the plate D, and with tongues, a, projecting downward therefrom, as seen in fig. 2, so as to pass through slots, d, in the plate D, and so that the tongues will hold the deflector H on to the plate, so that, while it may be readily removed (intentionally) therefrom, it cannot be accidentally removed.

The outer row of perforations through the plate D open directly into the chimney outside the deflector, while those within the circumference of the deflector open directly into the deflector, as seen in fig. 2. The open base permits the air to pass thus freely and in great quantity directly to the blaze. The deflector is removable, for the purpose of trimming the wick.

By this construction, the chimney, at its base, is little affected by the heat from the blaze, so that, at any time, the chimney may be removed by taking hold near its base, and all extra attachments for securing the chimney are dispensed with, the internal vertical springs E being the only means, and all that is required, for securing the chimney to the burner.

We do not claim supporting this chimney upon hooks dependent from the burner, so as to support the chimney below the flame; but

What we claim as new and useful, and desire to secure by Letters Patent, is—

The perforated plate D, in combination with the deflector H and the base, B, when the said plate is arranged in the manner described, and constructed in one and the same piece with the vertical springs E and the chimney supporters F, substantially as set forth.

ROB'T HOADLEY,
HENRY A. SHIPMAN.
